PROCESS FOR PRODUCING IMPROVING
PRODUCTS FOR PELTS, FURS, HAIRS,
AND TEXTILES OF ALL KINDS

Elmar Proft, Berlin-Lichterfelde, Germany, assignor to Vereinigte Glanzstoff-Fabriken A.-G., Wuppertal-Elberfeld, Germany, a corporation of Germany

No Drawing. Application February 7, 1938, Serial No. 189,275. In Germany February 11, 1937

5 Claims. (Cl. 260—513)

This invention relates to a process for producing improving products for pelts, furs, hairs, and textiles of all kinds.

As is well known the readily soluble alkali salts of aliphatic monocarboxylic acids form the basis of the usual washing process. The said salts, commonly referred to as washing soaps, possess however, as was already known, a series of drawbacks since the substances referred to on the one hand are very readily decomposed with flocculation by means of acids, such as for example sulphuric acid, and on the other hand they are flocculated out by the hardness formers of water, such as calcium, magnesium, and the like, with formation of insoluble alkaline earth metal soaps. The usual washing soaps also show similar drawbacks when they are used as scrooping, softening, fulling, wetting, foaming, cleansing, and emulsifying agent, e. g. for treating pelts, furs, hairs, textiles of all kind, such as wool, silk, cotton, flax, artificial silk, cellulose wool and the like. The preparation of soluble compounds of aliphatic nature which act similarly to the known soaps for washing purposes and other, e. g. textile, purposes, but do not possess the said disadvantages of decomposition in acid medium or flocculation out in the present of alkaline earths, has therefore been an old problem of the chemical improving art.

One attempt in this direction set out from cetyl alcohol obtainable from spermaceti, which was converted in turn into the iodide, the sulphur compound, and finally by oxidation into cetyl sulphonic acid. This classical way which leads actually to the true sulphonic acid, unfortunately possesses the drawback that it starts out from an expensive raw material which can be procured only in comparatively limited quantity and which ought to be reserved for other purposes of use. Finally, carrying out the chemical change through the iodide is also very expensive.

A direct way has, however, also been tried, by directly treating solar oil with fuming sulphuric acid. It is true that in this way aliphatic sulphonic acids are obtained, but the direct employment of the radical agent is accompanied by an extensive resinification and even carbonising of the paraffin compounds and consequently dark colouring of the products obtained, so that the utilisation of this way on an operative scale had for the most part to be given up again.

It will be gathered from the historical development and the foregoing example with which the industry has already concerned itself, that there exists a great interest in the production and use

of such sulphonic acids. In actuality, in contradistinction to the classical washing and setting agents, they are characterised by the fact that they are stable in acids, for example 20% and higher percentage sulphuric acid, as well as 5 in strong alkalies, such as soda lye. The latter is the more noteworthy since the corresponding sulphuric acid esters, which frequently are falsely recommended as sulphonic acids, are readily saponifiable structures and consequently in many respects cannot be compared with the true sulphonic acids in practical use.

Below a new way is described which is characterised by the fact that a start is made from a cheap natural product occurring in unlimited 15 quantities and nevertheless a good and satisfactorily acting end product in the form of a mixture of aliphatic sulphonic acids is obtained without the starting product or its derivatives undergoing any appreciable decomposition or carbonis- 20 ing in the course of the process. The new process starts out from mineral oil, crude or purified, or from individual fractions of mineral oil, e. g. from petroleum, or some other fraction of mineral oil. 25 The mineral oil portion or fraction is first of all chlorinated, preferably to an extent such that chiefly monochlorparaffins are formed.

From investigation of the mineral oil portion in question as regards the boiling points of the individual fractional portions one can calculate 30 out the approximate average molecular weight and accordingly calculate beforehand the necessary chlorine absorption and subsequently measure out by weighing. In the case of chlorination care is to be taken that the same is carried out 35 at not too high temperature, preferably below 40° C., and if necessary, according to the circumstances, with assistance of cooling.

The chlorination mixture is thereupon treated 40 with hydrosulphides (NaSH) or soluble sulphides (Na₂S). The mercaptans or sulphides produced are then oxidised by means of a powerful oxidising agent, such as for example nitric acid.

By choice and concentration of the oxidising 45 agent, as well as the temperature, the oxidation can be conducted so that pre-eminently the sought aliphatic true sulphonic acids are formed.

If the oxidation is carried out to a limited extent by choice of a milder oxidising agent or 50 by reducing the concentration of the same, or by moderating the reaction temperature, then, in addition to the sulphonic acids, amongst other things also disulphides are formed, and it is even possible by limitation of the oxidation as indi- 55

cated so to conduct the process that these latter products are chiefly formed.

It has also been found that the halogenation products, more particularly chlorination products, of mineral oil and its fractions can be directly converted into a mixture of utilisable paraffin sulphonlic acids by treating them with alkali sulphites, more particularly in the hot and under pressure. In this way the corresponding alkali sulphonates are obtained.

Example I

Chlorinated petroleum, prepared by leading chlorine into the technical fraction 160°-280° C. and which contains 21 parts by weight of chlorine substantially in the form of monochlorides, is mixed in a quantity of 2 kg. with an alcoholic KSH solution. The latter solution consists of 5 litres of denatured alcohol in which 1.5 kg. of KSH have been dissolved. The mixture is heated to boiling for 5 hours under reflux, and thereupon the oily mercaptans are separated off from the alcoholic treatment liquid in almost quantitative yield. 1.9 kg. of the mercaptans obtained are now treated little by little with 8 kg. of 30% nitric acid under reflux whilst heating up to the disappearance of the oil. The aqueous solution obtained is evaporated down up to the point of removal of the retained nitrous compounds and of the water. The product obtained is a semi-solid light brown water soluble mass permeated with crystals, and contains the desired sulphonlic acids.

Example II

The mercaptans obtained according to Example I are mixed in a quantity of 1.9 kg. with 15 kg. of diluted 15% nitric acid and heated under reflux for 4 to 5 hours. The light yellow oil floating on the top is separated off from the aqueous products in a separating funnel and essentially contains the lower oxidation stages produced, more particularly in the form of disulphides. They may be washed with water and dried over calcium chloride.

The aqueous products are evaporated down as in Example I in order to expel water and volatile nitrous products. The residue contains the sulphonlic acids described in Example I.

Example III

The petroleum chlorinated as in Example I is treated in a quantity of 2 kg. with 13 kg. of sodium sulphite solution which contains 1.3 kg. of sodium sulphite (Na_2SO_3) and the mixture is heated in autoclaves to 150-160° C. for 10 hours. The non-interacted chlorination products of the petroleum form the upper layer of the treatment liquid and are separated from the aqueous portions in a separating funnel and if necessary or desired subjected to a renewed treatment either alone or in admixture with further chlorination products of petroleum. The aqueous portions separated off contain the sought sulphonlic acids in the form of the sodium salts and may be evaporated down to dryness. The chlorination products of the mineral oil, more particularly of petroleum, may also be interacted with potassium sulphite or ammonium sulphite to form the corresponding alkali sulphonates.

Example IV

The mercaptans obtained under Example I are, in a quantity of 1 kg., stirred up with 28

litres of water to which 1.75 kg. of commercial potassium permanganate has previously been added. The mixture is boiled at a temperature not exceeding 100° C. until the oily parts have disappeared. The interaction is generally finished in about five hours. The reddish solution, which still contains unused potassium permanganate, is decomposed in the hot with the necessary quantity of oxalic acid in order to destroy the potassium permanganate remaining over. 10 The manganese dioxide separated out is removed from the solution by filtration. The colorless solution contains the sought sulphonlic acids in the form of the potassium salts and may be concentrated by evaporation.

In spite of the fact that the starting product, namely mineral oil and its fractions, is not a unitarily defined body, but is a natural mixture of numerous paraffin bodies and paraffin-like bodies, it has been found that nevertheless end 20 products can be obtained in the sulphonation process which are quite usable for the various technical purposes indicated. This is the more surprising since the starting products themselves are not a mixture of pure normal paraffins, and 25 therefore are not merely a more or less large section of a homologous series of the same, but comprises also secondary and tertiary paraffins, and even unsaturated olefinic-like compounds. Finally it is also noteworthy that in all mineral 30 oils and fractions thereof, including those from American sources, there are still certain quantities of aromatic compounds.

In spite of this complex and variable composition of the starting products, it is possible, 35 as numerous experiments have shown, to obtain within the scope of the present process light colored products utilisable with advantage in the technics. In the majority of cases the products can be obtained in high yield. It is particularly 40 remarkable that by certain of the sulphonation methods, more particularly by the oxidation of the corresponding mercaptans, also disulphides or mixtures of the same are obtained which are characterized by a particularly good wetting 45 action. The disulphide-mixture obtained from the mineral oil and its fractions is an oil-like, light yellow product of great stability towards acids.

The products obtained are suitable for the 50 most diverse purposes, for treating pelts, furs, hairs, textiles, such as wool, silk, cotton, flax, artificial silk, cellulose wool and the like. They may be used for this purpose as scrooping and softening agents and for improving the full- 55 ness. They have for the most part an outstanding wetting and frothing action which makes them suitable for use in other industries as well. They possess satisfactory cleansing powers and have proved to be outstanding emulsifying 60 agents. They also possess a noteworthy fat-splitting action.

Having now set forth the invention as required by the patent statutes, what is claimed is:

1. A process for making an agent for treatment of pelts, furs, hairs and textiles of all kinds, comprising heating the halogenated product of mineral oil with a substance selected from the group consisting of hydrosulfides and sulfides 70 and then reacting the sulfhydrated product with an oxidizing agent.

2. A process for making an agent for treatment of pelts, furs, hairs and textiles of all kinds, comprising heating the halogenated prod- 75

uct of mineral oil with a hydrosulfide to form mercaptans and then reacting the mercaptans with an oxidizing agent to form the corresponding sulfonic acids.

5 3. A process as claimed in claim 2, wherein the oxidizing agent consists of nitric acid.

4. A process as claimed in claim 2, wherein the oxidizing agent consists of a permanganate.

5. A process as claimed in claim 2, wherein the oxidizing agent consists of hydrogen peroxide.

ELMAR PROFFT.
